GAS TORCH

Edward S. Huff, Dearborn, Mich.

Application October 21, 1931, Serial No. 570,197

2 Claims. (Cl. 158—27.4)

My invention relates to gas torches and objects of my improvements are to provide an improved torch that may be readily assembled, that will not fire back so as to burn the hand of the operator and that will form a concentrated flame of special intensity at a definite point.

I accomplish this object in the device illustrated in the accompanying drawing, in which:—

Figure 1 is a section on the broken line I, I, 10 Figure 4.

Figure 2 is a sectional view on the line II, II, Figure 1, looking in the direction of the arrows.

Figure 3 is a detail plan view, the parts being partly separated to illustrate their construction 15 and method of putting the same together.

Figure 4 is an elevation partly in section on the line IV, IV, Figure 1, looking in the direction of the arrows.

1 is a hollow cylindrical handle. 2 is a gas tube 20 coaxial with the handle 1, said tube is screw threaded at its ends and at one end engages a flanged nut 3 with its screw threads, and at the other a plug 4. The flange of the nut 3 is of the same diameter as the handle 1, and it engages against the end of said handle. The flange nut 3 and the plug 4 form the end walls of the handle.

The plug 4 is provided with a flange 4a which is 25 cut out at regular intervals to form the slots 4b to admit of the engagement of lugs 1a, 1a, 1a (Fig. 3) in the cut out portion of the flange 4a. The tube 2 engaging coaxially with the nut 3 and plug 4 hold the same firmly against the ends of the handle 1.

30 Under the lugs 1a, 1a, 1a, the metal of the plug 4 is scooped out, as indicated in Figure 1, and there is formed a passage 4c for air through the wall of the plug opening to the scooped out portion. These scooped out portions open through 35 the end of the handle but do not open to the interior of the handle.

2a is a small delivery passage for gas under 40 pressure from the tube 2. The end of the tube converges to the center of the passage, through the plug 4, and the openings 4c permit air to enter 45 back of the aperture at 2a.

5 is a tube of uniform cross section, forming a continuation of the passage through the plug 4. A jet of gas under pressure is delivered from the 50 aperture 2a, centrally of the pipe, or chamber, 5 and acts to form a combustible mixture with the air entering through the holes 4c, and to thoroughly mingle the air and gas and force the same forward by its energy of motion.

55 6 is a nozzle fitted upon the pipe 5, at its outer

end, and so constructed that the combustible mixture coming from the pipe 5 will have a smooth and uninterrupted surface on entering the nozzle 6. The inner walls of the nozzle 6 converge uniformly from the delivery end of the pipe 5 to the outer end of the nozzle 6. Such walls, if continued, would meet at a point 7, as shown in Figure 1.

I have found that by this construction the air and gas is thoroughly mixed in the pipe 5, and 65 the advancing column of combustible mixture is gradually diminished in cross section by the walls of the nozzle 6, and that very intense heat is thereby produced at the point 7.

Should a back-fire occur it will be projected 70 through the scooped out portions at the periphery of the plug 4 and will not burn the hand of the operator.

What I claim is:—

1. In a gas torch the combination of a cylindrical handle having lugs formed at its engaging end, a plug provided with a peripheral flange, 75 said flange being slotted at intervals and said lugs fitting into said slots, said slots opening at the end of the handle but closed against the interior of said handle, and an air passage leading inward from the slotted portion of said plug under the lugs formed at the edge of the handle.

2. In a gas torch the combination of a cylindrical handle having lugs formed at its engaging 85 end, a plug provided with a peripheral flange, said flange being slotted at intervals and said lug fitting into said slots, said slots opening at the end of the handle but closed against the interior of said handle, and an air passage leading 90 inward from the slotted portion of said plug under the lugs formed at the edge of the handle, a coaxial aperture through said plug, a nut adapted to engage the other end of said handle and a tube having its ends screw threaded and engaging 95 said plug and nut.

EDWARD S. HUFF.
